UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

TRAIN CONTROL.

Application filed May 2, 1924. Serial No. 710,536.

This invention relates to automatic train control systems, and more particularly to means for protecting a train when moving from a siding into a block already occupied 5 by another train.

In certain train control systems of the speed control type, the minimum speed limit for a danger or occupied block is not imposed under control from the trackway until 10 after the train has traveled some distance. For example, in one well known type of system, a so-called cam is connected to the car wheels at a suitable control point in the rear of the stop signal or entrance to the 15 danger block, and this cam turns slowly as the train advances, providing a gradually decreasing permissive speed, the cam eventually assuming an ultimate or minimum speed position and remaining in that position to establish a continuing minimum 20 speed limit. A system of this type, it will be noted, is predicated on the assumption that a train will ordinarily pass through a caution block before it enters a danger block; but in practical operation it may happen for some reason that a train will enter 25 a danger block without having traveled over the distance required to run the cam down to its minimum speed position, with the result 30 that the minimum speed limit will not be set up at the entrance to such danger block as it should be. For instance, it often happens that a train, moving in a clear block, backs into a siding to allow another 35 train in the rear thereof to pass it, after 40 which the train in question leaves such siding and follows said another train. In this case, it will be evident that the cam or other slow action device may not have assumed its ultimate and minimum speed position at 45 the time the train in question enters the danger block in which the other train is moving. It will be noted that train control apparatus of this kind, in itself does not afford adequate protection in the case just 50 mentioned, because only caution speed restriction is imposed, whereas the train should be restricted to a danger or minimum speed.

55 In accordance with the present invention, it is proposed to solve this problem by providing a danger speed restricting device which is immediately effective upon initiation to impose a minimum speed restriction and which is initiated if two conditions con-

currently exist, these conditions being present when a train leaves a siding and moves into a danger block, but not very often at least, under ordinary operating conditions encountered in practice. These conditions 60 are (1) danger traffic conditions manifested on the vehicle by suitable means in communication with the trackway ahead; (2) an existing speed of less than a certain value, for instance such as that imposed in a danger 65 block. More specifically, it is proposed in accordance with the present invention to provide a suitable stick device which may only be picked up if traffic conditions ahead are clear, and which will only be dropped 70 if both traffic conditions are dangerous and the speed at which the train is moving is less than a certain predetermined value, this stick device being used to impose a danger 75 speed restriction when it is in its abnormal deenergized or active condition.

Other objects, purposes, and characteristic features of the invention will in part be pointed out hereinafter and in part be obvious from the following specification and 80 the accompanying drawing.

In describing the invention in detail, reference will be made to the accompanying drawing, in which a trackway having a siding associated therewith has been shown, together with suitable trackway equipment, and in which a railway vehicle, together with the car-carried apparatus for controlling the same and embodying the present 85 invention, has been conventionally shown. 90

Although the present invention in its broad aspect is applicable to various types of train control systems, employing either continuous or intermittent control from the trackway, the embodiment of the invention shown discloses what is commonly known as a continuous inductive control system, employing a two-position car relay and single phase trackway energy. The characteristic features of construction and 95 operation of a continuous inductive control system of this type are now generally known and recognized in the art, so that a simplified and diagrammatic illustration, together with a brief explanation, will suffice 100 to make clear the applicability of his invention to such a system, without illustrating or describing in detail the continuous inductive control system.

Trackway apparatus.—Referring to the 110

drawing, the present invention, although applicable to any type of block signal system, employing either alternating or direct current track circuits, has been shown applied to direct current track circuits. In the arrangement shown, the track rails 1 are divided by insulating joints 2 into blocks, the block I and the adjacent ends of the two other blocks H and J having been shown. Since the various blocks are the same, like parts of each block have been designated by like reference characters having distinctive exponents. At the exit end of each block is provided the usual track battery 3, connected across the rails in series with the secondary of a transformer 4, which secondary may serve as the usual series limiting resistance of the track circuit. At the entrance end to each block and across the rails is bridged a direct current track relay T. Although the present train control system may be used in connection with railways having wayside signals of the color light, position light, or semaphore type, or may be applied to a system which does not include such wayside signals if suitable cab signals, which for convenience have not been shown, are provided, the train control system has been shown applied to trackway apparatus including semaphore signals Z, which have been conventionally shown without illustrating their well known circuits and control devices. Under clear traffic conditions in each block, as the block I, the block, as H, next in the rear, in addition to the direct current supplied thereto, as heretofore explained, is supplied with alternating current from the transformer 4. In the arrangement shown, a line transformer 5 has its primary winding connected to a suitable source of alternating current, illustrated as a transmission line P, and has its secondary winding connected to the primary winding of the transformer 4 by a circuit including the front contact 6 of the track relay T of the block next in advance. In the particular arrangement shown, a siding S comprising track rails 7 enters the main track in the block I near the entrance thereof. The switch points for this siding S are operated manually or by power in the usual manner by means which, for convenience, has been omitted from the drawing. This siding S is provided with insulating joints 8 and is cross bonded in the usual manner, so as to provide fouling point protection. It should be noted that alternating current is present in the track rails of a block in advance of a train only if both the portion of said block in advance of said train and the next block in advance are clear. This control of the alternating current in a block is accomplished in two different ways. 65 In the first instance, no alternating current

is present ahead of a train in a block when the next block in advance is occupied, because alternating current is cut off at the primary winding of the transformer 4 by the track relay of the block ahead; and in the second instance, even though alternating current may be applied to the track rails from the transformer 4 of a block in question, such current is not able to reach a train in the block if that block is occupied by another train ahead, because said another train will shunt the alternating current away from the train in question, so that no alternating current may be detected by this following train.

Car-carried apparatus.—As heretofore mentioned, a car-carried apparatus includes a two-position main car relay MR which is controlled from the trackway. This relay MR has been conventionally shown and is normally maintained energized by current induced in coils 11 and 12 disposed over the track rails in front of the train, illustrated by the axle 13 and wheels 14. This induced current is amplified by a suitable amplifying device A, shown diagrammatically, which includes suitable thermionic or vacuum tube amplifiers, tuning devices, and the like, well-known to those skilled in the art of continuous inductive train control systems.

The main car relay MR may be a split-phase alternating current relay of the induction type, using a rotor or a vane as the movable element; or if the amplifying device A includes a rectifying tube, this relay may be a direct current relay of the tractive type. The movable element or armature of the relay MR is biased by counterweights or springs in the usual way to a deenergized position, and operates suitable contact fingers shown conventionally. In the type of system shown, the car relay MR has only two controlling positions, energized and deenergized.

As heretofore mentioned, the present invention is particularly applicable to train control systems in which a delayed action device is used; and as shown the delayed action device is a distance element operated in accordance with the progress of the vehicle along the track, similar to the arrangement shown in the patent to Simmen, No. 1,150,309, dated August 17, 1915, and in the form also shown in the application of W. K. Howe, Ser. No. 38,132, filed July 16, 1915. Since this type of speed control apparatus is described at great length in this patent and pending application, a diagrammatic illustration and a brief description of this apparatus will suffice.

In the arrangement shown, there is provided a cam shaft 20, suitably journalled, having a mutilated gear 21 and a cam 22 keyed at opposite ends thereto. This cam

shaft 20 is biased to the normal position shown by a spring 23. Directly over the mutilated gear 21 is disposed a worm 24 fixed to a tiltable shaft 25 which is driven 5 from the wheels of the vehicle through a suitable universal joint (not shown), so that this worm may be moved up and down freely without interfering with the driving of this shaft by said wheels. The shaft 25 10 is normally held in the raised position, so that the worm 24 is out of engagement with the mutilated worm wheel 21, by a cam starter magnet CS, which is energized 15 through a front contact 26 of the main relay MR by a suitable source of energy which, for convenience, has been designated by the terminals B and C. It will be noted that deenergization of the cam starter magnet CS allows the shaft 25 and worm 24 to 20 assume a lower position by reason of gravity or a suitable spring, so that the worm 24 operatively engages the mutilated worm wheel 21, and that continual rotation causes the cam 22 to be rotated until the worm 24 25 reaches the mutilated portion of the worm wheel 21. It will be noted that the operative connection between the coil of the cam starter magnet CS and the shaft 25 comprises a core 27 having a forked end pivotally secured to a sleeve 28 rotatable on 30 the shaft 25. The various positions assumed by the cam 22, as will more clearly appear hereinafter, determine different permissive speed limits at which the train may travel 35 without incurring an automatic brake application, and in practice the cam is shaped to set up speed limits at different points in a block which conform with the speeds of a brake performance curve taken on a track 40 having a certain grade by a train of a certain class, so that the speed limits set up are ideal for certain standard or average conditions. These various positions of the shaft 30 are determined by the arm 31 pinned to the shaft 30, which engages a grooved collar 32 of a centrifugal speed-responsive device, or governor G. This governor G has been conventionally illustrated and is mounted on the shaft 33, also driven 45 from the wheels of the vehicle, and includes centrifugal weights or fly balls 34 which tend to move outwardly by the action of centrifugal force and move the grooved collar downwardly, and a compression coil 50 spring 35 opposing the centrifugal action of these fly balls, so that the collar 32 is moved downwardly as the speed of the train increases. To the shaft 30 is pinned another arm 36 which has a floating lever 37 55 connected to the free end thereof, the other end of this floating lever having a roller 38 bearing against the surface of the cam 22 by reason of the tension spring 39.

It is thus noted that the mid-point of the 60 floating lever 37 responds both to the posi-

tion of the cam 22 and the speed as manifested by the speed-responsive device G. All that is necessary to control the train if the speed, as determined by the speed-responsive device G, is too high as compared 70 with the position the cam 22 assumes, is to cause an application of the brakes if this mid-point of the floating lever moves a predetermined distance toward the right. A contact for controlling a suitable brake control apparatus, when the mid-point of this floating lever assumes a predetermined position, has been illustrated and comprises a movable contact 40 and a stationary contact 41, which contacts are normally held in contact with each other by means of a roller 42 75 engaging a sector 43 operatively connected to the mid-point of the floating lever 37 by the link 44, so that transverse movement of the mid-point of the floating lever causes 80 rocking of the sector about its pivot. The sector 43 is provided with a cut away portion and thereby allows the contact 40 to separate from the contact 41, so that these contacts are operated to break a circuit when 85 the actual speed of the train is in excess of the permissive speed established by the cam 22.

The speed shaft 30, in addition to determining the position of the lower end of the floating lever 37, has a contact actuator 47 keyed thereto, which is adapted to open and close circuits at various speeds. In the particular arrangement shown, a contact 48, having a roller 49 pivotally connected thereto, is biased toward the left, so that this roller 49 engages the edge of the actuator 47, and the contact itself engages a stationary contact 50. Another movable contact 51 is operatively connected to the contact 48 by an insulating strip or link 52, so that the contacts 48 and 51 move together in response to the position of the roller 49. Adjacent the contact 51 is a stationary contact 53 which is normally out of engagement 100 with the contact 51. The actuator is so shaped that the contacts 48-50 and 51-53 assume the position shown, if the speed of the train is greater than, say, 20 miles per hour, but assume the reversed position, so that the contacts 48-50 are open and contacts 51 and 53 are closed, if the speed is less than this value. The purpose of these contacts will be more particularly pointed out in connection with the operation of the 105 system hereinafter.

It is contemplated in accordance with the present invention to automatically apply the brakes in a manner so that the engineer cannot prevent stoppage of the train as soon as the speed is excessive, as determined by the cam 22. Since the present invention is not directed to any particular type of brake applying apparatus, and since any one of the various devices heretofore recog- 110

nized for this purpose may be employed in a system embodying the present invention, no particular type of brake applying means has been shown in detail. It is assumed 5 that such a brake applying device will be pneumatically operated, and an electro-pneumatic valve EPV, which is electrically controlled, has been shown for this purpose.

Under normal clear traffic conditions, the 10 electro-pneumatic valve EPV is maintained energized through a circuit which may be traced as follows:—beginning at terminal B of a suitable source of energy, wire 56, cam-governor contacts 40 and 41, controlled 15 by the sector 43, wires 57 and 58, front contact 59 of a suitable stick relay SR, more particularly described hereinafter, wires 60 and 61, winding of the EPV, wire 62, back to a common return wire C, connected to 20 the other terminal of said source of energy.

It is thus noted that the device EPV assumes its deenergized position as soon as contacts 40—41 open as far as the apparatus thus far described is concerned. It will, 25 of course, be noted that a certain distance of travel is necessary after the main relay MR has been deenergized, before the cam 22 assumes its ultimate position (the position at which the worm 24 reaches the 30 mutilated portion of the worm wheel 21) and the minimum or low speed restriction is imposed. This feature in delaying the time at which the ultimate speed restriction takes place is characteristic of the system 35 shown in the patent and patent application respectively referred to heretofore. In accordance with the present invention, as heretofore mentioned, it is proposed to have this minimum speed restriction, assumed to 40 be 20 miles per hour, imposed instantly under predetermined concurrent conditions of the main relay MR and the speed of the train; and the low speed stick relay SR, together with the contacts controlled 45 by the cam 47, have been provided for this purpose.

This stick relay SR, of the usual construction, has been shown conventionally, and includes two separate windings, the 50 upper winding 65 of which is energized, when the main relay MR is in its energized position through the contact 66 of this relay, by a circuit readily traced in the drawing. With the stick relay SR once energized, its front contact 67 is closed, and if 55 the speed of the train is above 20 miles per hour, a stick circuit including the lower winding 68, the front contact 67, and the speed contacts 48—50, is closed. It will 60 thus be noted that with this relay SR energized, by its stick circuit, it will assume its deenergized position if both the relay MR is deenergized and the speed of the train is less than 20 miles per hour. With the 65 stick relay SR de-energized, the front contact

59 of this relay opens, thereby interrupting the normally closed circuit for the device EPV, heretofore traced. If the speed of the train at this time is below the low speed of twenty miles per hour, the contacts 51—53 are closed and form, together with the wires 69 and 70, a shunt or multiple path around the front contact 59 of the low speed relay SR, so that the valve EPV is maintained energized. It will be noted that the valve EPV is at once deenergized upon dropping of the low speed relay SR, if the speed of the train is at that time above 20 miles per hour, regardless of the position of the cam 22. Consequently, if the train stops or runs at a speed less than the minimum under caution or danger traffic conditions, it can not thereafter run faster than the minimum speed until the car relay MR has been re-energized from the trackway 70 and acts to pick up the low speed relay SR. 75

Operation.—Under ordinary traffic conditions, as soon as the train enters a caution block, the relay MR drops, because the alternating current has been cut off of such block by the track relay of the block ahead, as is obvious from the drawing. As the train moves through such a caution block, the cam 22 turns and gradually restricts the 80 permissible speed of the train, bringing the train to a minimum speed of, say, 20 miles per hour before it reaches the danger block. As the train moves into the danger block this relay MR remains in its deenergized 85 position, because the alternating current, if on the track rails, is shunted by the train ahead. It should be noted that, if traffic conditions clear up while a train is traveling in a caution block, the relay MR is immediately energized, regardless of the position of the train in the block, so that the 90 train may again proceed restricted only to a maximum speed limit, set up by the cam 22 in its restored position.

Let us assume that a train, equipped with the apparatus described, is moving from left to right through the blocks H and I, with another train following close behind, and that the first train by schedule, or train order, is required to take the siding S shown, 105 so as to allow the other train to move ahead. As the first train ahead backs into the siding, the cam 22 will remain in its normal position until the receiving coils 11—12 come back of the insulating joints 8, this 110 on the assumption that traffic conditions ahead are clear. As soon as the train gets back of the fouling point, the main relay MR and the cam starter magnet CS are de-energized so as to start the cam 22 in rotation. However the train, although it has backed far enough into the siding to allow 115 the other train to pass, has not moved the cam 22 appreciably from its normal position. As soon as the other train has passed 120

the siding, the train in question will naturally leave the siding to follow the other train. Now, this other train may stop for some reason before it leaves the block I; and it will be evident that under such circumstances the following train coming from the siding S should be placed under the minimum speed restriction, since it would then be traveling in a danger or occupied block. 10 As far as the cam 22 and its control from the trackway are concerned, however, the train coming from the siding S might be permitted to run at a speed much higher than the minimum speed, depending upon 15 how far the cam 22 had been driven toward its ultimate or minimum speed position by the time the train passed from the siding on to the main track. In the particular case assumed, with the train backing into the 20 siding under a clear signal, it can be seen that the cam 22 would be substantially in its normal maximum speed position when the train came out on to the main track, permitting the train, as far as the cam is concerned, to accelerate to a comparatively high 25 speed. If the train had entered the siding S from the opposite end, the cam 22 would have been partly run down to some intermediate speed position while the train 30 moved along the siding, inasmuch as the car relay MR would be deenergized and connect the cam to the car wheels while the train was running on the siding which would not be supplied with train control 35 current.

The low speed relay SR, however, and its manner of control provides for such contingencies as above explained. Assume that the train pulls out of the siding S with the cam 22 in its maximum speed position, or 40 at least at some relatively high speed position. While this train is on the siding, back of the fouling point, the car relay MR is deenergized, breaking the pick-up circuit for the relay SR. Also, since the train on the siding is at a standstill, the contacts 48-50 are opened, breaking the stick circuit of the low speed relay SR. Consequently, both energizing circuits for the relay SR are interrupted; and irrespective of the position of 50 the cam 22, the minimum speed limit is enforced by contacts 51-53 as the train pulls out from the siding. If the block I is a danger block, by reason of the passage of the other train by said siding in the normal 55 direction of traffic, the car relay MR on the train in question now moving off of the siding remains deenergized, because the train control current in the portion of the block 60 I between the two trains, is shunted out by the other train ahead. The low speed relay SR remains deenergized and the minimum speed limit remains in force so long as the train ahead stays in the block I. In the 65 two-position type of system shown, the low

speed limit also continues in force until the block I becomes a clear block, or until the following train is able to pick up train control current. As soon as the block in which the train is running becomes clear and the 70 car relay MR picks up, the low speed relay SR is reenergized by closure of its pick-up circuit; and the train may thereafter proceed at maximum speed, the cam 22 being restored to the normal position at the same 75 time.

From this explanation it will be understood that, whenever a car equipped with apparatus according to the invention stops or slows down below a predetermined low 80 speed limit while the main car relay MR is deenergized, the minimum speed limit is thus rendered effective, and the train cannot thereafter proceed faster than this minimum speed limit until the car relay MR has 85 been again energized. Such an arrangement provides full protection for trains coming off of sidings into occupied blocks, and does not materially interfere with train movement under regular operating conditions. In the particular two-position type 90 of system disclosed, the same control, namely deenergization of the car relay, exists in a caution block as in a danger block; and for this reason a minimum speed limit is enforced under some circumstances where not 95 essential for safety. For example, as a train enters a caution block below the minimum speed, it is held down to this minimum speed until the block clears. This is not true of a 100 system where a distinctive control is provided for a danger block different from a caution block, the relay SR in such a case not being deenergized, although in a caution block the speed is low or the train has 105 stopped, and is deenergized only in a danger block. It will be obvious that it is proper to have the low speed relay SR deenergized in a danger block, since the minimum speed limit should be enforced. 110

The invention is applicable to the well known three-position type of continuous inductive control system, employing a three-position car relay. It is also evident that the invention is not restricted to a continuous 115 inductive control system of any type, but in its broad aspect is applicable to any type of system employing a speed-responsive device on the car, with a delayed action device for setting up the minimum speed restriction, irrespective of how the control is obtained from the trackway under unfavorable conditions. It should also be understood that a thoroughly complete system meeting all practical operating requirements would include other devices and features not herein disclosed. For example, cab signals or indicators, enforcement of acknowledgment of signal indications, control for unequipped territory, provision for 120 125 130

operation of the locomotive or car either end ahead, and other features may in practice be incorporated with the particular means of this invention without altering the nature 5 of the invention or its utility and advantages. It should also be understood that various changes, additions and modifications may be made in the particular construction shown and described, without departing 10 from the nature or scope of the invention or the broad concept of means underlying the same.

What I claim is:—

1. In a train control system of the continuous inductive type in which gradually reducing permissive speed limits are set up by suitable mechanism when adverse traffic conditions are set up as manifested by the absence of current normally flowing in the track rails ahead of the train, the combination with brake control means for effecting a brake application if the actual speed of the train exceeds the permissive speed set up by said mechanism, of means for setting up a low permissive speed limit abruptly which the vehicle cannot exceed without incurring a brake application, said last mentioned means being rendered active if dangerous traffic conditions are manifested and 30 the speed of the train is below a predetermined value simultaneously.
2. In a train control system of the continuous inductive type in which gradually reducing permissive speed limits are set up by suitable mechanism when adverse traffic conditions are set up as manifested by the absence of current normally flowing in the track rails ahead of the train, the combination with brake control means for effecting a brake application if the actual speed of the train exceeds the permissive speed set up by said mechanism, of means rendered active to set up a low permissive speed limit which the vehicle cannot exceed without incurring a brake application if the speed of the vehicle is less than a predetermined value while dangerous traffic conditions are manifested, said last mentioned means if once active remaining active until favorable 50 traffic conditions are again manifested.

3. Car-carried apparatus for automatic train control systems of the speed control type comprising, a speed restricting device normally in its inactive condition which if 55 momentarily actuated assumes its active condition, and means for actuating said device if the speed at which the train is traveling is less than a certain predetermined value and traffic conditions, as manifested by influences transmitted by apparatus for continually transmitting influences from the trackway to a suitable car-carried influence receiving device, are dangerous.

4. An automatic train control system 60 comprising, a delayed action permissive

speed device which is delayed in accordance with the progress of the vehicle along the trackway when initiated and which if initiated gradually reduces the permissive speed set up to a predetermined permissive 70 speed limit, a device responsive to the actual speed of the vehicle, means for applying the brakes when the actual speed exceeds the permissive speed, separate means which if active applies the brakes if the speed of the train is above a predetermined low value, and means effective only if traffic conditions ahead are adverse and the speed of the train is reduced below a predetermined low value 75 for rendering said separate means active. 80

5. In an automatic train control system, the combination of a normally energized control means on a railway vehicle for indicating the conditions of traffic ahead, means partly on the vehicle and partly along the trackway and acting through an intervening air-gap for controlling said control means, a delayed action device governed by said control means initiated when said control means is deenergized and which sets up 90 a minimum permissive speed limit when it reaches its ultimate condition, an unretarded device for setting up a minimum permissive speed limit when both said control device is in its deenergized condition and the speed of the vehicle is below a certain value, and means for causing an automatic brake application if the speed of the vehicle is higher than the permissive speed set up by either of said devices. 95

6. An automatic train control system comprising, a brake setting device, a device responsive to the actual speed of the vehicle, permissive speed mechanism, and means for rendering said permissive speed mechanism active to set up a low speed limit only when traffic conditions ahead are dangerous and the speed as manifested by said speed responsive device is below a certain value, and means for actuating said brake setting device if the actual speed of the vehicle exceeds the permissive speed set up by said mechanism. 105

7. An automatic train control system comprising, a car-carried control relay, means for energizing said relay in response to current flowing in the track rails ahead of the train, a speed responsive device, a stick relay having a stick circuit including its own contact and a contact governed by said speed responsive device which is open when the speed of the vehicle is below a certain value in series, and means for restricting the speed of the train if said stick relay is deenergized, or said control relay is deenergized. 115 120

8. Car-carried apparatus for train control systems comprising, a speed responsive device, a stick relay, a circuit for energizing said relay including a front contact of said relay and a contact governed by said 130

speed responsive device and open when the speed of the train is below a certain value, a permissive speed device controlled by said relay and effective when said relay is deenergized, a brake setting device, and means for actuating said brake setting device if the speed of the train exceeds the permissive speed set up by said permissive speed device.

10 9. Car-carried apparatus for train control systems comprising, a speed responsive device, a stick relay, a circuit for energizing said relay including a front contact of said relay and a contact governed by said speed responsive device and open when the speed of the train is below a certain value, a control relay, a permissive speed mechanism including a permissive speed cam which sets up gradually decreasing speed limits as the 15 train proceeds through a block of trackway when initiated, a brake setting device, means for rendering said permissive speed mechanism active to set up permissive speed limits when either of said relays are deenergized, and means for actuating said brake setting device if the speed as manifested by said speed responsive device exceeds the permissive speed set up by said mechanism.

10 10. In a train control system, car apparatus comprising, a speed-responsive device driven from the car wheels, a movable element determining by its position the limiting permissive speed for the car and adapted to be connected to the car wheels, brake applying means operated whenever the actual speed of the car exceeds its permissive speed represented by the position of said movable element, a low speed device for establishing a minimum speed limit independently of the 15 position of said movable element, and means controlled from the trackway for rendering said low speed device effective only when simultaneously the speed of the car is below a predetermined minimum and unsafe traffic 20 conditions ahead exist.

11 11. Car equipment for train control systems adapted to protect train movement from sidings on to main tracks comprising, in combination with speed control apparatus for enforcing predetermined speed limits under caution and danger traffic conditions after an interval of delay, of a low speed device capable of enforcing a minimum speed limit independently of said apparatus, and 15 automatic means for rendering said low speed device effective on a car running from a siding into a danger block.

12 12. Car equipment for train control systems comprising, a control relay governed 15 from the trackway and assuming a predetermined danger condition in an occupied or danger block, a speed-responsive device driven from the car wheels, a low speed stick relay effective when deenergized to establish 20 in cooperation with said speed-responsive de-

vice a minimum speed limit which the car cannot exceed without an automatic brake application, a pick-up circuit for said low speed relay interrupted when the control relay assumes said danger condition, and a 70 stick circuit for said low speed relay including contacts operated by the speed-responsive device and opened at all speeds above said minimum speed.

13. Car apparatus train control systems 75 comprising, a speed-responsive device driven from the car wheels, minimum speed contacts operated by said device and opened at all speeds above a predetermined minimum, a low speed stick relay, a brake setting appliance, a normally closed circuit including said appliance and having two branches in multiple, one of said multiple branches including said minimum speed contacts and the other branch including a front contact 80 of said low speed relay, a control relay governed from the trackway and deenergized under dangerous traffic conditions, a pick-up circuit for the low speed relay opened upon deenergization of said control relay, and a 85 stick circuit for said low speed relay controlled by the speed-responsive device and opened whenever the speed of the car is 90 above a predetermined low speed.

14. In a train control system of the type 95 employing a permissive speed device changeable in accordance with the distance traveled by the car, the combination with a car relay controlled from the trackway and governing the permissive speed device, a slow speed relay 100 adapted when deenergized to enforce independently of said permissive speed device a minimum speed limit which the car cannot exceed without an automatic brake application, and automatic means for deenergizing 105 the low speed relay effective only if the car have a speed between zero and a predetermined minimum speed in territory where danger traffic conditions are manifested by the deenergized condition of said car relay. 110

15. In an automatic train control system of the continuous inductive type, the combination with a main relay on the vehicle which assumes an energized condition in response to current flowing in the track rails 115 ahead of the vehicle under favorable traffic conditions ahead, speed contacts closed if the speed of the vehicle is below a predetermined value, a brake control device normally energized through a circuit including said 120 speed contacts, a stick relay having a pick-up circuit closed if said main relay is in an energized condition, a stick circuit for said stick relay including contacts closed only if the speed of the vehicle is above a certain 125 value, and contacts on said stick relay closed if said stick relay is energized for shunting said speed contacts, whereby said stick relay is deenergized to enforce said predetermined speed value if the train travels at less than 130

said certain speed while said main relay is deenergized.

16. In an automatic train control system of the continuous inductive type, the combination with a main relay which assumes an energized condition in response to the flow of current in the track rails ahead of the train, a permissive speed device normally maintained inactive and which if rendered active, sets up gradually decreasing speed limits, another permissive speed device, for abruptly setting up a low speed limit, a device for indicating the actual speed of the train, a brake control device, means for actuating said brake control device if the actual speed of the vehicle is higher than that set up by either of said permissive speed devices, and means for rendering said another permissive speed device active if the speed of the train is reduced below a predetermined value.

17. In an automatic train control system of the continuous inductive type, the combination with a main relay which assumes an energized condition in response to the flow of current in the track rails ahead of the train, a permissive speed device normally maintained inactive and which if rendered active sets up gradually decreasing speed limits, another permissive speed device for abruptly setting up a low speed limit, a device for indicating the actual speed of the train, a brake control device rendered active if the actual speed exceeds the permissive speed limit set up by either of said permissive speed devices, and means for rendering said another permissive speed device active if the said main relay is deenergized and the speed of the train is less than a certain value concurrently.

18. In an automatic train control system of the continuous inductive type, the combination with a main relay which assumes an energized condition under favorable traffic conditions in response to the flow of current in the track rails ahead of the train, a permissive speed device normally maintained inactive by said main relay and

which if rendered active sets up gradually decreasing speed limits, another permissive speed device for abruptly setting up a low speed limit, a device for indicating the actual speed of the train, a brake control device which is rendered active if the actual speed exceeds the speed limit set up by either of said permissive speed devices, and means for rendering said another permissive speed device active so long as said main relay is deenergized if the speed of the train has been less than a certain value at any time during the time said main relay was deenergized.

19. Car-carried apparatus for automatic train control systems of the speed control type, comprising a speed limiting device normally in inactive condition means for actuating the device on decrease of train speed below a predetermined value, and means causing said actuation of the device to be effective to limit train speed only provided traffic conditions, as manifested by apparatus on the car, are not clear.

20. Car-carried apparatus for automatic train control systems of the speed control type, comprising, a speed limiting device normally in inactive condition, means for actuating the device on decrease of train speed below a predetermined value, and means responsive to traffic conditions for causing said actuation of the device to render such device effective to limit the speed of the train.

21. Car-carried apparatus for automatic train control systems of the speed control type, comprising, a speed limiting device normally in inactive condition, means for actuating the device on decrease of train speed below a predetermined value and means responsive to traffic conditions for causing said actuation of the device to render such device effective to limit the speed of the train only if traffic conditions are not clear.

In testimony whereof I hereby affix my signature.

CHARLES S. BUSHNELL.
